UNITED STATES PATENT OFFICE.

KARL SCHNEIDER, OF PFORZHEIM, GERMANY, ASSIGNOR TO EMIL WITZENMANN, OF PFORZHEIM, GERMANY.

METALLIC HOSE.

1,200,533.

Specification of Letters Patent. Patented Oct. 10, 1916.

Application filed October 9, 1914. Serial No. 865,835.

To all whom it may concern:

Be it known that I, KARL SCHNEIDER, a subject of the German Emperor, and resident of Oestliche Karl-Friedrich strasse 5 134, Pforzheim, in the German Empire, have invented an Improved and Novel Metallic Hose, of which the following is a specification.

This invention relates in general to a metallic hose in which the tightness is increased by means of a special cylindrical helix wound over and upon the windings of the appropriately shaped metal strip or band forming the hose at the place or rim where 10 the outer part or rim of a winding takes over, and presses upon, the inner part or rim of the adjacent winding; this pressure being now considerably increased by that of said special helix whereby the tightness of the 15 hose is correspondingly improved.

In particular my invention relates to metal hoses of the kind, in which one of the two rims of the metal strip or band, viz. that remaining at the outside of the finished hose, 20 is so shaped that a packing can be inserted between the overlapping metal parts, the rim in question forming a groove which is situated just opposite to the outer surface of the inner part or half of the metal strip 25 or band, and is adapted to receive said packing which thus is under the mutual pressure of the hose-forming metal parts. Now, the arrangement of the said special helix is such that it presses the grooved part 30 with its packing upon the flat metal part of the winding below it, whereby the tightness is increased in such a measure that the hose may be employed also for fluids which are under a comparatively great pressure. In 35 order to maintain this great tightness even if the hose is bent in curves of short radius, the special helix is so connected with the grooved part mentioned that no relative axial movement or displacement can occur, 40 as will become more clear from the accompanying drawing which shows a part of my improved hose partly in side view and partly in longitudinal section.

A is the metal band which forms in its 45 sectional shape an inner rim a^1 and an outer rim a^2 . More accurately the outer rim consists of two parts a^2 a^3 , of which the latter forms a groove containing a packing b . This packing is located between the parts 50 a^3 and a^1 of the band A, and it is subjected

not only to the own pressure of the wound band A in general, or of the parts a^2 a^3 in particular, but also to the pressure of a separate helix B wound just upon the part or groove a^3 and pressing it against the packing b which, of course, is pressed in its turn against the part or rim a^1 . The strength of the helix B is, of course, appropriately chosen. It may be wound upon the grooved part or rim a^3 either simultaneously with 60 winding the band A, i. e. forming the hose, or upon the wound band, i. e. upon the thus far finished hose. The sectional shape of the rim part a^3 may be different from that shown, as may also the shape of the helix 65 wire at its inner surface where it is in contact with said rim part a^3 , but at any rate the shape of the two parts in question must be such that an axial displacement of the helix B with respect to the hose A is completely prevented.

If the hose is intended for conducting a hot fluid, such, for instance, as steam, the helix B is preferably made of a metal having a lesser coefficient of expansion than has the 80 metal which the hose proper is made of. For instance, iron may be chosen for the hose proper in such a case, but bronze for the helix B.

The inner diameter of the helix B, when 85 this latter is in proper position upon the hose, corresponds, of course, exactly to the outer diameter of the hose at the place a^3 , but if the helix would, or could be removed, it would somewhat contract; the difference represents the tension with which 90 the helix presses upon the packing at the place a^3 . The outer diameter of the helix B is preferably at least the same as that of the hose at the place a^2 , or a little more, so that 95 the hose proper is secured against external friction.

Having now fully described my invention what I claim and desire to secure by Letters Patent is:—

1. In a metal hose, the combination with 100 the hose proper, and with a packing situated between the overlapping hose parts, of a helix spirally wound under tension and so arranged as to be adapted to compress said 105 packing between said overlapping parts.

2. In a metal hose, the combination with 110 the hose proper, of a helix so arranged as to be adapted to press the overlapping hose parts against each other; said helix con-

sisting of a metal having a lesser coefficient of expansion than has the hose metal.

3. A hose consisting of a sheet metal strip formed spirally with each convolution lapping and interlocking with the convolution adjacent thereto, and a packing between the overlapping parts of the convolutions, in combination with a spring helix formed around the overlapping parts of the convolutions to cause them to press the packing against the underlapping parts of the convolutions.

4. A hose consisting of a sheet metal strip formed spirally with each convolution lapping and interlocking with the convolution adjacent thereto, and a packing between the overlapping parts of the convolutions, in combination with a spring helix formed around the overlapping parts of the convolutions to cause them to press the packing against the underlapping parts of the convolutions, and the inner face of said helix and the coöperating outer face of the strip being shaped to prevent the axial displacement of the hose and helix.

5. A hose consisting of a sheet metal strip formed spirally with each convolution lapping and interlocking with the convolution

adjacent thereto, and a packing between the overlapping parts of the convolutions, in combination with a spring helix formed around the overlapping part of the convolutions to cause them to press the packing against the underlapping parts of the convolutions, and the outer diameter of the helix being approximately equal to the outer diameter of the hose proper.

6. A hose consisting of a sheet metal strip formed spirally with each convolution lapping and interlocking with a convolution adjacent thereto, and a helix wound over and upon the windings of the metal strip at the place where the outer part of its winding takes over, and the inner face of said helix and the outer face of the hose proper having interlocking portions to prevent axial displacement of the hose proper and helix.

In witness whereof I have hereunto signed my name this fifteenth day of September, 1914, in the presence of two subscribing witnesses.

KARL SCHNEIDER.
